(57) **CLAIM**

The ornamental design for a towel rack, as shown and described.

DESCRIPTION

FIG. 1 is a perspective view of a towel rack showing my new design.

FIG. 2 is a front view thereof.

FIG. 3 is a rear view thereof.

FIG. 4 is a left side view thereof, shown enlarged in scale.

FIG. 5 is a right side view thereof, shown enlarged in scale.

FIG. 6 is a top view thereof; and,

FIG. 7 is a bottom view thereof.

Any shading and cross-hatching are not features of the design but are utilized to illustrate the surface contours of the towel rack design in the drawings.
